AUTOMATIC YARD SWITCH

John L. Jensen, St. Paul, Minn., assignor to Railroad Permanent Way Products Corp., Ashtabula, Ohio, a corporation of Ohio

Filed Mar. 3, 1965, Ser. No. 436,897
18 Claims. (Cl. 246—445)

The present invention relates to improvements in railway stub switches of the type in which the ends of the moving rails are substantially squarely truncated, as opposed to split switch constructions in which the moving rail ends are sharply pointed. More particularly, the present invention relates to the novel combination of a unitized prestressed concrete foundation with a greatly simplified stub switch construction to provide a completely "winter proof" railway switch that is eminently suited to automatic operation.

In stub switches as known in the art, lengths of rail are movably mounted between the approaching and the trailing side of the switch, the switch or radius rail lengths being adapted to form continuations of the fixed rails, and to make connection between the main rails on the approaching side of the switch, and either the main rails or the siding (turnout) rails on the trailing side of the switch, to the extent that they are moved into one position or the other.

Around the turn of the century, stub switches fell into disuse and disfavor with maintenance men and were replaced with split switches because stub switches, in the forms in which they have been produced in the past, have been subject to important and very serious disadvantages. Among these disadvantages may be mentioned the objection that the heavy strains and impacts imparted by the cars to the switch, have in the course of the wear of the switch, resulted in the stub rails failing to make perfect alignment between the rails on the approaching and trailing sides of the switch. This failure to make proper alignment or "lapping" as it is technically called, resulted in accidents and derailments and has been one of the causes of the stub switch being considered unsafe and impracticable. Another objection to a well known design of stub switch was that the running rails on each side of the switch crept under traffic and crowded the switch rails against the fixed rails so that the switch was sometimes rendered inoperable. Another objection common to stub switches was that the switch rails were not always lined up properly with the fixed rails, and wheels with sharp flanges had a tendency to climb the rails. Thus, it was very difficult to maintain the old stub switch in good surface, gauge and alignment and these constituted important considerations that lead to the decline in popularity of stub switch constructions. Further, the old stub switch provided only intermittent tie plate or slide plate support at each switch tie and consequently there was no positive means of maintaining a constant gap distance at the throw point between the ends of the switch rails and the lead and turnout track connecting rails. As the rails expanded during hot weather, the gap would tend to close, causing a binding condition. In cold weather the gap would tend to become too great, thus causing undue pounding and wear.

Accordingly, practically all switches now in use upon the railroads of this country are of the knife blade or point type (split switches), in which a pair of long tapering rail members are used. Each of the switching rails is ordinarily about sixteen feet in length and usually, one end of each switch rail is of the same cross section as the track rails, and is fixedly mounted. This switch rail member is then cut so as to taper gradually to a very thin edge at its free end, and such free end is movable toward and away from the main track rail for a distance which is ordinarily about five inches. Such tapered rails are known

2

as points and the switch itself has been known as a point, knife blade or split switch. In practical use, split switches are very unsatisfactory for the reason that they are expensive to produce in that they consist of a large number of parts which must be made by special equipment not found in an ordinary machine shop. Moreover, the cutting of rails to form the switch points is an expensive operation and the life of the switch points is necessarily short, due simply to the small amount of material present, thus concentrating the wear. Hence, the thin ends wear rapidly by reason of their small cross section and frequent renewals are necessary. This is objectionable as the installation of a split switch and the renewal of worn points is expensive by reason of the time necessarily consumed in such operations.

Another disadvantage is that the points easily become bent or damaged and this has caused the derailment of trains. For example, if the switch points are thrown to permit movement of a train from the main track to a side track, one of the points is held against a main track rail. In case a car should be backed down the main track in the direction opposite to that of the train to be switched, the wheel flanges will pass between the main track rail and the switch point and bend the latter, whereby it becomes permanently bent or misshaped and the head rod by which the points are operated may also become bent at the same time. After this has occurred, the switch point cannot be thrown close enough to the main track rail to function properly to permit a train to move on either the main or the side track, but may permit some of the wheels to move along the main track while others are diverted by the switch point and derailment of the train ensues. The main objection, however, is that the switch points are easily rendered inoperative by ice and snow as well as dirt and other foreign substances between the parts of the switch and in particular, between the rails of the switch, such that the switch parts must be cleaned or freed, often at considerable expense.

Railroad experience with split switches has shown that in periods of heavy snowfall and blizzard conditions, operating costs increase substantially while at the same time productivity decreases. This is due in great part to the problems encountered with the operation of the present split switches. During these periods, it is necessary to sweep the points of the switches clean before they can be operated. Because of the now limited number of track laborers available and the difficulty of employing temporary help, the switch and engine crews must often spend a great deal of unproductive time waiting for switches to be cleaned. The result is not only increased track-labor costs for cleaning the switches but also increased handling costs per car.

Hence, stub switches have the advantage over the split or point switches now in general use in that they are not as subject to becoming clogged with ice, snow and foreign substances as split-point switches are. Moreover, stub switches are not open to the objection, frequently urged against split or point switches, that the extreme end of the switch rail is very readily bent or broken.

With these considerations, there is a clearly demonstrated need in the art for an improved railway switch which will not only avoid the disadvantages of the older forms of stub switches, but will also avoid the disadvantages of presently known split or point switches.

It is therefore among the principal objects and advantages of this invention to provide an improved stub switch which will be safe in use under the severest conditions of wear; which will not be subject to impairment by reason of temperature changes or the creeping of the rails; which will be capable of withstanding the shocks and strains imparted to it by heavily laden railway cars; and which will be of a simple and durable construction.

It is among other important objects and advantages of this invention to provide a stub switch that will be automatic in operation while solving the problem of sweeping out the switches and at the same time reducing the possibility of derailment.

It is among further important objects and advantages of this invention to provide an improved stub switch wherein there are no switch points to get out of alignment; wherein there is no jamming from rail creepage; wherein there are no gauge problems; wherein there are no levelling problems; wherein no stock rails are required; wherein no adjustment requiring rail braces are necessary; and wherein spike killed ties are eliminated.

It is among still other important objects and advantages of this invention to provide an improved stub switch having a minimum of moving parts and a novel and rigid foundation that will eliminate most maintenance costs; be non-clogging and thus eliminate snow removal problems; and provide long-lasting, trouble free and safe operation.

Other and further objects of this invention, together with an appreciation for the advantages thereof, will become increasingly apparent to those skilled in the art as this description proceeds.

Broadly stated, the foregoing objects are achieved and the foregoing advantages are realized by combining a greatly simplified two rail stub switch construction with a unitized support, completely eliminating ties. The unitized support comprises a prestressed concrete foundation of one piece construction for supporting the stub switch construction of the invention. The improved and greatly simplified stub switch is one in which the free ends of two partially fixed switch rails are deflected to line up with either the lead track or the turnout track in order to effect the desired movement through the switch. Preferably, the switch rails are mounted on the unitized concrete support by interposing sole plates therebetween, and desirably interposing durable rubber rail seats between the sole plates and the unitized support. In this manner, there is provided a stub switch that eliminates the objections and problems encountered with the split switch.

More particularly, the objections to tapered or knife blade switch points are done away with and the diversion of traffic from main to side track is effected by means of movable track members of large cross-sectional area, preferably equal to that of the main line rails. The present stub switch is mounted on a precast, prestressed concrete foundation instead of switch ties since such a concrete foundation provides continuous support under the full length of the switch. The concrete foundation is an integral unit under both switch rails and thus insures positive track surface and uniform track gauge and alignment throughout the length of the switch. The base or sole plates also provide continuous longitudinal support under both rails through the entire switch thus eliminating objections that have resulted with the use of switch support by intermittent tie plates and slide plates. The switch rails and the lead and turnout track connecting rails are welded or otherwise securely attached to the continuous sole plates to maintain a constant gap distance at the throw point, thus preventing a binding condition or too wide a gap distance between the switch rails and the lead and turnout track connecting rails.

The invention also provides for automatic switch alignment for trailing movements over the switch wherein the switch track control circuit is desirably provided with motor driven cam action, known in the art such as to cause the switch operating mechanism to properly align the switch rails and lead rails.

The understanding of this invention will now be facilitated as reference is had to the accompanying drawings in which the same or similar reference numerals have been employed to depict the same or similar parts throughout the several views, and in which:

FIGURE 1 is a plan view illustrating a typical stub switch layout according to the invention, shown connected to broken out sections of main and turnout track;

FIGURE 2 is a cross-sectional view taken along line 2-2 in FIGURE 1 to show constructional details of the prestressed concrete foundation of the present invention;

FIGURE 3 is a broken out plan view, greatly enlarged, taken on the section lines 3-3 in FIGURE 1 to show constructional details of the switch rail movement connections;

FIGURE 4 is a broken out cross-sectional view, greatly enlarged and taken on the section lines 4-4 in FIGURE 2 to show constructional details of the switch rail movement connections; and

FIGURE 5 is a modified embodiment of the stub switch according to the invention showing guides and supports that may be employed therewith.

Referring to the drawings, the numerals 12 and 14 generally designate a pair of lead or main line rails, while 12a-14a designate lead or main line rails on the approaching side of the switch and 12t-14t designate the main line rails on the trailing side of the switch, and the numerals 16 and 18 designate a pair of turnout or siding rails. A stub switch structure designated generally at 10 and constructed according to this invention is interposed between the main rails 12a-14a on the one hand and 12t-14t on the other to provide connection to the turnout rails when desired. The stub switch structure, embodying rails 20 and 22 is mounted on a pair of longitudinally tapering steel base or sole plates 24 and 26 which in turn are mounted on rubber pads (FIGURE 2) 28 and 30 interposed between the base plates and the longitudinally and transversely tapering concrete foundation members indicated generally at 40 and 40' that in turn are connected together by the transversely tapering concrete cross ties or connecting members 50a and 50t. The main line and turnout rails are supported by the usual ties 11a and 11t, etc. As shown, the left hand ends of the switch rails 20 and 22 may extend beyond the ends of the supports 40 and 40', meeting and abutting with the main line rails 12 and 14a on one of the ties 11a. The right hand ends of the switch rails 20 and 22 fall short of the right hand ends of the supports 40 and 40', such that the right hand main line rails 12t and 14t, as well as the ends of the turnout rails 16 and 18, extend onto and are supported by the right hand ends of the foundation supports 40 and 40', reaching almost to the cross-tie structure 50t. The switch rails 20 and 22 are located on the base plates 24 and 26 respectively such that the major portion of each switch rail rests on its respective base plate with the remaining portions extending beyond the base plates to facilitate standard angle bar connections with the approaching lead track rails. For this purpose, holes not shown are provided in the switch rails at their approach ends to facilitate such angle bar connections. Both switch rails 20 and 22 are welded or otherwise securely attached for a short distance to the base plates at the approach end of the switch. The remaining unsecured portions of both switch rails are free to move on the base plates within the limits of the rail stops of which four are shown (FIGURE 1) for each switch rail, although more or fewer may be employed. As shown, the stops 261-263 and 241-243 limit the turnout track direction of movement for the switch rails 20 and 22, respectively, while the stops 262-264 and 241-243 limit the main line direction of movement. Rail stops are welded to the base plates to limit the deflection of the switch rails, and are designed to make contact with the rail web. The stops have rounded or pointed contact surfaces to prevent the accumulation of snow between the web of the rail and the stop.

In the embodiment shown, the switch is connected to the trailing main tracks 12 and 14, and to the turnout tracks 16 and 18 by means of the two lead track connecting rails 12t and 14t and the two turnout track connecting

rails 16^t and 18^t which may be of any rail section as required by the railroad. The connecting rails 12^t, 14^t, etc., are located on the respective base plates such that the left hand portion of each connecting rail rests on the base plates and the remaining connecting rail portion extends beyond the base plates at the trailing end of the switch to facilitate standard angle bar connections with the main tracks 12 and 14 and turn out tracks 16 and 18. It will be recognized that small gaps are left between the ends of the switch rails and the connecting track rails to permit smooth movement and accommodate any fluctuation in length due to temperature change. The connecting track rails 12^t and 14^t are welded or otherwise secured to the base plates for the full portion of their length resting on the base plates. As with the approach side, holes to accommodate standard angle bars for the rail section used are drilled in the connecting rails. The base plates 24 and 26 are tapered to vary in width from the approach end of the switch to the trailing end of the switch to provide a solid web or frog plate type support and connection between the corresponding main and turnout connecting rails. The base plates are securely attached by way of anchor bolts 248 and 268 to the concrete foundation which provides continuous support under the base plates for their full length and width. Rubber rail seat pads 28 and 30 of substantially the same length and width as the base plates are installed between the base plates and the concrete foundation.

The concrete foundation is either of precast, prestressed or precast reinforced design. It consists basically of two longitudinal beams 40 and 40' which are poured as an integral unit, being connected at two points by short reinforced beam sections or cross-ties 50^a and 50^t. As shown in FIGURE 2, the precast concrete beams 40 and 40' are each provided with tapering side portions 42 and a top portion 41. Longitudinal reinforcing rods 45 extend substantially through the entire length of the beams 40 and 40'. The longitudinal beam sections are desirably tapered in width from top to bottom to provide strong and stable support for the rails. The anchors for the anchor bolts are precast in the foundation.

Preferably, lateral reinforcing rods 47 are also provided to hold the longitudinal rods 45 in position, for example, by welding prior to pouring of concrete. To this end, the rods 47 may be formed into a trapezoid shape such that all portions thereof are approximately equidistant from the respective outside surfaces of the concrete beam. Cross members 50^a and 50^t are each composed of upper surfaces 51 with tapering side walls 52. As shown in FIGURE 2, the cross members 51 are reinforced by lateral rods 54 and 55, each of the lateral rods passing a substantial distance into the beams 40 and 40^t. This may be accomplished, for example, by welding the rods 54 and 55 to the rods 45 prior to the pouring of concrete.

Switching is accomplished according to the invention by means of the switch rod, connecting rod, and clevis members shown. In particular, the switch control mechanism will drive the switch rod 62 which is connected by means of the clevis member 63 to the switch rail 20. The switch rail connecting rod 61 is installed between the switch rails a short distance back from the throwing point ends of the switch rails to maintain standard gauge between the rails. The connecting rod should have a design capacity of at least 5000 lbs. in both compression and tension. The connecting rod is designed to be adjustable in length and is desirably provided with clevis type connections at the ends. The clevis members may be bolted to the switch rails by suitably placed holes passing through the web thereof to facilitate attachment to the throw rod.

As shown in the drawings, the switch connecting rod 61 is provided on the other side of the switch rail 20 and opposite clevis member 63, the same being connected to rail 20 by means of the clevis 64. Connection to switch rail 22 is provided by means of clevis 65. As is well known in the art, each clevis may be comprised of

5 a collar portion connecting two flange-like members in a U-shaped arrangement, the flange members having registering holes for receiving a bolt which will also pass through the eye of a similar bolt disposed between the flange members.

10 For the purpose of illustrating the invention for use with standard American gauge railroads, the overall switch length may be twenty-eight feet while the switch rails 20 and 22 may be approximately twenty feet in length and may be of any desired rail cross-sectional shape that will meet the requirements of the railroads. The switch rails may be located on the base plates such that about seventeen and one-half feet of each switch rail rests on its respective base plate with the remaining portions extending beyond the base plates for purposes already noted, for a distance of about two and one-half feet. The approach ends of both switch rails are welded or otherwise securely attached for a distance of about three and one-half feet to the base plates. The remaining portion, approximately fourteen feet in length, of both switch rails are free to move on the phase plates within the limits of the rail stops. This is an important feature of the invention as many prior art switches were freely hinged mounted, while others subject to binding were usually bolted or clamped in place.

20 The two lead track connecting rails and the two turnout track connecting rails are about eight and one-half feet in length and may be of any rail section as required by the railroad. The connecting rails are located on the 25 base plates such that approximately three and one-half feet of each connecting rail rests on and is welded to the base plates, while the remaining 5 feet, more or less, extends beyond the base plates as already noted. The gap distance between the ends of the switch rails and the connecting track rails is approximately $\frac{1}{4}$ inch.

30 The track center for the turnout track at the throw point is $4\frac{1}{4}$ inches more or less to the left or to the right of the center line of the lead track. Both switch rails must therefore be deflected $4\frac{1}{4}$ inches more or less at 35 the throw point in order to line up with the turnout track connecting rails. The switch rails when deflected for the turnout movement through the switch, form a curve with a radius of about 279.64 feet along the switch rail arc length of about fourteen feet. The curve radius may be increased by reducing the deflection at the throw point to approximately $3\frac{1}{2}$ inches and using flared guides at the end of the throw rails as indicated generally by reference numerals 74 and 76 in FIGURE 5. For left hand turnouts, the ball of the left lead track connecting rail and ball of the right turnout track connecting rail are planed to provide a throat flangeway distance of about $2\frac{3}{4}$ inches between the connecting rails at the throw point. Also shown in FIGURE 5 are a plurality of stop supports 243, 263 which may be used for added support when desired. As will be recognized these are optional features according to the invention.

40 The sole or base plates are three-quarters ($\frac{3}{4}$) inch in thickness, about twenty-one feet in length and vary in width from about $12\frac{1}{2}$ inches at the approach end of the switch to about $18\frac{1}{2}$ inches at the trailing end of the switch. Each base plate is securely attached to the concrete foundation by approximately thirty-one $\frac{3}{4}$ -inch anchor bolts such that the base plates provide continuous support for their full length and width. The spacing and location of the anchor bolts are shown in FIGURE 1. 45 As an example, the right and left end bolts may be about six inches from the end of the base plates, while all other anchor bolts may be on twelve inch centers, although some may be staggered.

50 The rubber pads are about $\frac{1}{4}$ inch thick and of about the same length and width as the base plates. The rail stops are of $\frac{3}{4}$ -inch material and are designed to make contact with the rail web.

55 A switch rod is installed between the switch rails approximately 7 inches back from the throwing point ends

of the switch rails by means of two $1\frac{1}{16}$ inch holes provided in each switch rail approximately 3 inches and 11 inches respectively from the throw point to maintain standard gauge between the rails. The connecting rod should have a design capacity of at least 5000 lbs. in both compression and tension. The connecting rod is designed to be adjustable in length and with clevis type shoe connections at the ends.

The concrete foundation, of either precast, prestressed or precast reinforced design consists of two parallel longitudinal beams, each approximately 21 feet in length. The longitudinal beams are 16 inches more or less in depth and are tapered in width ranging from about 23 inches at the top to 30 inches at the bottom. In contrast to the base plates, the top and bottom widths of the longitudinal beams are relatively constant. The cross members are about eighteen inches wide at the top and about twenty-five inches wide at the bottom but have the same depth as the longitudinal beams, and while the longitudinal beams may have stub ends, the cross members, if separable from the longitudinal members, would have inwardly tapering ends as shown in the drawings. Preferably, the cross members are parallel to each other and perpendicular to the longitudinal beams. The cross members may be disposed about three feet six inches to about four feet four inches from the longitudinal beam ends, measuring from top surfaces, and the cross members may be about ten feet two inches apart also measuring from the top. Viewed from the top, all sides taper according to the preferred embodiment such that the bottom is about three and one-half inches away. Since the rail gauge is four feet and eight and one-half inches, the longitudinal beams will be about two feet five inches apart along their inside base edges, and about seven feet five inches apart at their outside base edges.

The longitudinal beams are provided with a plurality of longitudinally extending steel reinforcing cables or rods 45 which are prestressed prior to or after the pouring of concrete to form the beam. The prestressed cables or rods 45 are each prestressed for example to a tension of 14,000 pounds for longitudinal beams. Instead of the members 47, the longitudinal beams may be additionally reinforced with a No. 5 gauge steel spiral tie 48 (FIGURE 4) having a 6-inch pitch provided over the full length of the beam, the spiral ties preventing lateral or vertical misalignment of the prestressed strands of cables or rods 45. After the cables or rods 45 have been bonded into position by the spiral ties 48 on the 6-inch pitch throughout the length to which the beam is to be made, the concrete is poured into the form and the beam is cast.

By carefully controlling the mix of concrete, a minimum compressive strength is placed on the beam by prestressing cables or rods 45 in the amount of 5000 pounds per square inch after 28 days whereas the ultimate prestress loading of the finished beam is 727 pounds per square inch. If the beams are to be used for railroad use they have a vertical height of 16 inches whereas if the beams are to be used in an urban rapid transit system they may have a vertical height of only 8 inches.

The concrete cross beams 50a and 50t are also prestressed and precast and provided with a plurality of prestressed reinforcing steel rods or cables 54 and 55, which are suitably placed in the prestressing form prior to pouring of the concrete. The rods 54 and 55 extend through the length of the cross beams and project out of each end of the same. The rods 54 and 55 are then welded to the rods 45.

While the drawings disclose the cross beams as having a vertical height approximately the same as the height of the longitudinal beams it is, of course, within the scope of the present invention that the cross beam may have different heights than the beams 40 and 40'. While any desired number of cross beams 50a and 50t may be used between a pair of the longitudinal beams, it has been

found that two of such cross beams suitably anchored to the respective longitudinal beams are sufficient to provide adequate strength and sufficient rigidity to the supporting structure for the traction rails and switch movement. Since the longitudinal concrete beams are supported along their full length by the usual type of railroad bed, the shear on the longitudinal beams is negligible and it has been found that such beams are capable of carrying at any one point 61,700 pounds, which provides a considerable margin of safety beyond the amount of stress normally encountered.

The present stub switch may be driven (thrown) or operated by any of the presently approved switch machines, including those mounted between the tracks as indicated by reference numeral 71 in FIGURE 5, which switches may employ air cylinders; hydraulic cylinders; a screw dock device driven by electric or air motors; an eccentric cam driven by gear motor; or by any other desired means, such as any suitable manually operated switch throwing device.

As an example, the presently installed switch may be operated by a Union Switch & Signal M-1 switch machine. However, various other methods of operation are also suitable as will be hereinafter appreciated. The track circuitry is so designed that the track-fouling circuit will actuate the switch mechanism to properly align the switch for a trailing movement over the switch. If the electric current should be interrupted, the machine can be overridden and the switch thrown by hand. This switch will perform satisfactorily without the need for sweeping snow from it, even under severe snow conditions and "very heavy" switch movements.

As another example, the improved stub switch according to the invention was employed in a suitable testing installation. The two switch rails were each welded to $\frac{3}{4}$ -inch thick base plates mounted on the prestressed concrete foundation instead of on switch ties. A one-quarter inch thick rubber pad was installed between the base plate and the foundation. The base plates extended the full length of the twenty-one foot concrete foundation and were anchored securely to the foundation.

Each switch rail was 17 feet 4 inches long and each was welded to the base plate at one end such that each was movable at the other end for a distance of twelve feet. The free end had a $4\frac{1}{2}$ -inch throw and was provided with a flared guard as shown in FIGURE 5, eighteen inches in length and disposed on the gauge side to provide a normal flangeway for wheels. The fixed rails, which were welded to the base plates and separated from the switch rails by one-quarter inch gaps, were about ten feet long and were machined to provide a standard flangeway. The welding prevented the fixed rail from crowding into the switch rail. The system was entirely satisfactory with all types of rail traffic, even under heavy snow and ice conditions.

It is thus evident that the present invention overcomes the defects of prior art split and stub switches. For example, it is a familiar fact to those acquainted with the workings of railways that the shrinkage and expansion of the rails, caused by variations of temperature, seriously affect the operation of present switches. The switch rails, not being connected with the ties, are moved endwise bodily by the fixed rails whenever expansion and contraction occur, thus making the play between the ends of the rails at the switch-joint greater than at any other joint. In consequence of this, and in view of the fact that the slipping of the so-called fixed rails on the ties and at the joints is extremely variable, it is difficult to settle upon just the proper movement to allow for at the switch-joint. The result is that the rails are apt to "jam" at the switch-joint, so that they cannot be readily moved unless considerable space is allowed, in which case, when the rails are contracted, they are apt to be drawn off the head-block, or at least to be crushed or splintered by the hammering of the wheels. Moreover, if the rails are loosely

jointed, the traction of the engine wheels tends to drive them endwise and jam, or cause a gap at the switch-joint, as the case may be. However, the switch construction of the present invention remedies these defects, and provides a switch that will operate freely at all temperatures with the minimum play at the joints, as well as enjoy other advantages already noted.

It will be recognized that a stub switch constructed according to the present invention has been described and shown only by way of example in this specification and in the accompanying drawings, and it should be understood that the form described and shown is not the only one in which the invention may be embodied, and that changes may be made in the construction which is described and shown without exceeding the scope of the invention except as defined in the appended claims. Having thus described the invention, what is claimed as new and desired to be secured by Letters Patent is:

What is claimed is:

1. A stub switch construction comprising: a precast and prestressed concrete foundation, the concrete foundation providing an integral and unitary support for the switch construction to thereby insure positive track surface and uniform track gauge and alignment throughout the length of the switch; a pair of continuous longitudinal base plates disposed upon said concrete support; and a stub switch rail disposed upon each longitudinal base plate, a portion of each switch rail at the approaching end of the switch being fixedly secured to the respective longitudinal base plate, the remaining portion of each switch rail being freely movable from a position adjacent the rails of a main rail line on the trailing end of the switch and a position adjacent the rails of a turnout track on the trailing end of the switch.

2. The stub switch construction of claim 1 including rubber pads interposed between the top surface of the concrete foundation and each longitudinal base plate.

3. The stub switch construction of claim 1 including switching means comprising a connecting rod disposed between each of the stub switch rails, said connecting rod being connected to the respective stub switch rail by means of a clevis member; and a switch throw rod connected to one of said stub switch rails by means of a clevis member, the switch throw rod being responsive to a switch control and driving mechanism.

4. A stub switch construction comprising: a prestressed concrete foundation; a pair of base plates mounted on said foundation; a stub switch rail mounted on each base plate; a portion of each stub switch rail being welded to the respective base plate, each base plate being securely anchored to the concrete foundation; a rubber pad disposed between each base plate and the concrete foundation; and a plurality of fixed rails disposed at either end of said stub switch construction.

5. The stub switch construction of claim 4 wherein the base plates are steel of about three quarters of an inch in thickness.

6. The stub switch construction of claim 4 wherein the base plates and concrete foundation are each about twenty-one feet long.

7. The stub switch construction of claim 4 wherein the rubber pad is about one quarter inch in thickness.

8. The stub switch construction of claim 4 wherein the stub switch rails are shorter than the concrete foundation such that a portion of at least some of the fixed rails are disposed on said concrete foundation.

9. The stub switch construction of claim 4 wherein each stub switch rail is approximately seventeen to twenty feet long.

10. The stub switch construction of claim 9 wherein approximately twelve to fourteen feet of the stub switch rails are freely movable.

11. The stub switch construction of claim 4 wherein the free ends of the stub switch rails have a throw of approximately three and one half to four and one half inches.

12. The stub switch construction of claim 4 including a flared guide disposed on the gauge side of at least one stub switch rail to provide a normal flangeway for wheels.

13. The stub switch construction of claim 12 wherein each flared guide is approximately eighteen inches long.

14. The stub switch construction of claim 4 wherein the fixed rails are approximately ten feet in length, are separated from the switch rails by approximately one quarter inch gaps, and are machined to provide a standard flangeway.

15. The stub switch construction of claim 4 wherein the prestressed concrete foundation comprises: two parallel longitudinal members, and integral therewith and disposed at right angles thereto, two parallel cross members, each cross member being separated one from the other and from the ends of the longitudinal members.

16. The stub switch construction of claim 15 wherein both longitudinal members and cross members have tapering side edges.

17. The stub switch construction of claim 4 wherein the concrete foundation is reinforced with steel rods.

18. The stub switch construction of claim 4 wherein the base plates and rubber pads taper in width from the approaching ends to the trailing ends of the switch.
